United States Patent Office

Des. 189,720
Patented Feb. 7, 1961

189,720

MICROPHONE

Louis R. Burroughs, Buchanan, Mich., assignor to Electro-Voice, Incorporated, Buchanan, Mich., a corporation of Indiana

Filed Feb. 4, 1960, Ser. No. 59,266

Term of patent 14 years

(Cl. D26—14)

FIG. 1

FIG. 2

FIG. 3

FIG. 4

Figure 1 is a front elevational view of a microphone embodying my new design, the bracket for supporting the microphone being shown in broken lines;

Figure 2 is a top plan view of the microphone illustrated in Figure 1;

Figure 3 is a bottom plan view of the microphone illustrated in Figures 1 and 2; and

Figure 4 is a front elevational view of the microphone illustrated in Figures 1, 2, and 3.

The essential features of my new design are shown in solid lines in the drawing.

I claim:

The ornamental design for a microphone, as shown and described.
